Patented Aug. 3, 1976

240,801

BOTTLE CARRYING CASE

Rodney D. Marchetti, 1739 Oakdale Drive,
Waukesha, Wis. 53186

Original design application Jan. 10, 1972, Ser. No.
216,903, now Patent No. 235,512. Divided and this application Nov. 25, 1974, Ser. No. 526,695

Term of patent 14 years

Int. Cl. D9—03

U.S. Cl. D9—179

FIG. 1

FIG. 2

FIG. 3

FIG. 4

FIG. 1 is a perspective view of a bottle carrying case showing my new design;

FIG. 2 is a sectional view taken adjacent and parallel to the bottom;

FIG. 3 is a sectional view similar to FIG. 2 but showing a modified form of my new design wherein the divider panels are all of equal width; and

FIG. 4 is a fragmentary, partially broken away perspective view of the bottom of the interior of either form.

This is a division of application Ser. No. D. 216,903 filed Jan. 10, 1972, now Pat. No. D. 235,512 patented June 24, 1975.

I claim:

The ornamental design for a bottle carrying case, as shown and described.
